(57) **CLAIM**

The ornamental design for a patient table, as shown and described.

DESCRIPTION

FIG. 1 is a front elevational view of a patient table showing our new design;

FIG. 2 is a back elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a perspective view taken generally from the top, front, right-hand side thereof.

The broken lines in the drawings depict portions of the patient table that form no part of the claimed design.
